METHOD AND MEANS FOR ESTIMATING THE PHLEGMATIZING PROPERTIES OF WAXES AS APPLIED TO HIGH EXPLOSIVES

John W. Rowen, South Fairlington, Va., and Albert J. Phillips, deceased, late of Arlington, Va., by T. Dixon Dudderar, administrator, Dover, N. J.

No Drawing. Application January 15, 1947,
Serial No. 722,278.

4 Claims. (Cl. 250—71)

(Granted under the act of March 3, 1883, as amended April 30, 1928; 370 O. G. 757)

1

The invention described herein may be manufactured and used by or for the Government for governmental purposes without the payment to us of any royalty thereon.

Due to the insistent demand for explosives of increased brisance there has come into use, in recent years, a number of explosives which were already known but which had been considered too sensitive, i. e., too sensitive to shock and to friction to be of military value. Their manufacture, loading and transportation has been considered hazardous and much effort has been expended in finding ways to desensitize them in order to increase the safety factor in connection with their use.

Experience has shown that these undesirable properties may be modified and largely eliminated by coating the explosives with various inert materials such as waxes known by the following trade names: Amberwax (Petroleum Wax, melting point 82—86° C., Bareco Oil Co., manufacturer); Santowax (Hydrocarbon wax, melting point 83° C., Monsanto Chemical Co.); Aristowax (Paraffin wax, melting point 71—74° C., Petroleum Specialty Co.); Acrawax (Synthetic wax, melting point 95—97° C., Glyco Products Co.); Albacer wax (Synthetic wax, melting point 95—97° C., Glyco Products Co.); Pentawax 177 (85% pentaerythritol tetrastearate, 15% dipentaerythritol hexastearate, melting point 70—73° C., Heyden Products Co.); Pentawax 286 (melting point 120° C., Heyden Products Co.); or natural resins such as Karaya gum, gum elemi, gum copal, gum dammar, or synthetic plastics such as polystyrene, methyl methacrylate, polyvinyl acetate or coumarone-indene, etc. Materials of this type are generally referred to as "waxes" throughout this application.

In the search for suitable coating agents and processes of application it has been found necessary to investigate the properties of a large number of agents and application techniques. The latter is important because various samples of explosives all containing the same percentage of "wax" may differ greatly in their sensitivities because of differences in the method of application. It, therefore, became highly desirable that there be available a procedure for the detection of uncoated, sensitive spots and uneven distribution of the "wax" in the "wax"—explosive mixture. Such a technique would be useful in the quality control of explosive properties in the manufacture of phlegmatized explosives.

This invention relates to a method and means for estimating the coating and phlegmatizing

ability of "waxes" as applied to high explosives. It aims in particular to provide a means for estimating the sensitivity of high explosives which have been subject to such a phlegmatizing process. This invention is based upon our discovery that there is a definite relationship between the nonfluorescing areas of a "wax" coated explosive composition and its sensitivity. Our researches have shown that light coming from a mixture of coated and uncoated crystals, exposed to ultraviolet light of certain wavelengths, varies from a deep purple for uncoated material to a brilliant, yellow white or blue white for coated material, depending upon the nature of the "wax" used.

15 The hue of the color is definitely related to the sensitivity of the explosive composition and this is a result which could not have been predicted in advance.

With the type of ultraviolet lamp and filter 20 commonly used, which produces a light having a maximum intensity at 3660 angstrom units, it has been found that there is no visible fluorescence of highly nitrated high explosives when exposed to this light. Observations under ultraviolet light 25 are made in the following manner: (1) Hanovia analytic model; (2) an A-G-E Mercury Arc, or (3) an Arc lamp with iron electrodes in conjunction with a #9863 Corning filter or a triple filter consisting of the three following elements: (a) 30 10% copper sulfate solution, 5 mm. stratum; (b) a #9863 Corning filter, and (c) a nitrosodimethyl aniline solution (10 mg. per 100 c.c. H₂O), 5 mm. stratum. The fluorescing sample is observed through either an Eastman #2A filter or a double element filter consisting of didymium glass and K3 glass. With this arrangement reflected ultraviolet light is cut off from the eye or the camera. No special preparation of sample is necessary. Due to the passage of a small amount of visible 35 40 45 violet and red light through the filters used with these lamps, nonfluorescing specimens exposed to the light of the lamp take on a deep purple color. On the other hand, "waxes" exposed to this light fluoresce with a brilliant yellow, blue or white light.

We have found that as the amount and uniformity in distribution of the wax increased, the color of the sample rises from a deep purple through various shades to a brilliant blue, white or yellow color. Samples may be screened or observed without special treatment. The sample, usually about 1 gram, is evenly distributed in a small watch glass of 1 to 2 inches in diameter. However, even a few uncoated crystals or even 50 55 the uncoated face of a crystal may be readily

detected by its purple color in the mass of brilliantly fluorescing material. The microscope is used when one seeks evidence of preferential adsorption of unevenness of wax distribution on tiny crystal faces. The desideratum, of course, is that there be no purple visible in the coated specimen. It may be emphasized, therefore, that our method does not depend upon any measurement of the color, hue or intensity of the fluorescent light but is concerned solely with the purple areas of uncoated material.

The method of application of the wax as illustrated by examples given below exerts a very large effect with regard to the uniformity of coating. So that with the same explosive composition, the same "wax" and the same percentage of "wax" it is possible by examination in ultra-violet light to distinguish between samples as to the desirability of using one or another method of applying the wax. The characteristics of the samples are shown by the following table.

4
plosive, that is, in all examples pentaerythritol tetranitrate.

5	Exp. No.	Wax	Per Cent Wax	Degree of Coating ¹	Impact Sensitivity
10	1	None	0	Poor	18-21
	2	Albacer	9.2	do	30
	3	Acrawax	8.0	do	29
	4	do	8.3	Fair	38
	5	do	10.0	Very Good	74
	6	Ba Stearate	9.1	Fair	53
	7	DNT	38.0	Poor	23
	8	Pentawax 286	10.0	do	35
	9	Pets ²	5.0	Good	53
	10	Pentawax 177	8.1	Excellent	74
	11	do	13.1	do	100

15 ¹ This term is the opinion formed of the extent and homogeneity of the coating after inspection of the samples under ultra-violet light and with the aid of a microscope.

² Abbreviation for pentaerythritol tetrastearate.

As has been pointed out heretofore, the uncoated face or faces of a crystal of explosive might be detected by the examination in ultra-

Sample Number	Preparation	Per Cent Wax	Name	Impact Test 2 Kg. Wt., Cm.	Visual Estimate of Dark Non-fluorescing Areas
I	Coprecipitation	0	None	21-20	D*
II	do	10	Acrawax	31	++++
III	do	10	do		++++
IV	do	13.6	do	45	+++
V	do	13.6	do		++
VI	Slurry	10	Aristowax-Alox	55	++
VII	do	10	do	55	++
VIII	do	13.1	Pentawax-177	100	0
IX	do	8.1	do	80	+

*Entirely dark—no observable coated areas.

+ Unit of relative darkness—a few uncoated areas.

0 No dark areas—all exposed crystal faces coated.

The figures in centimeters in the 5th column, represent the heights in centimeters from which the 2 kilogram weight must be dropped in order to cause the explosive to detonate. Thus, not only does the examination in ultra-violet light furnish an indication as to the proper method of applying the wax but it also furnishes by visual examination an index as to the sensitivity of the coated product.

Examples of the preparation of "wax" coated explosive compositions are given as follows:

Example 1.—Slurry process

A suspension of 50 grams of pentaerythritol tetranitrate in 100 cc. of water was heated to 90° C. while being stirred rapidly. The appropriate "wax" (8.8 grams suspended in 20 cc. of water at 90° C.) was then added over a 4-minute interval. The mixture was vigorously stirred while being cooled to 40° C. The waxed explosive was then filtered off and examined under ultra-violet light, no drying being necessary.

Example 2.—Coprecipitation process

Pentaerythritol tetranitrate (7 grams) and the appropriate "wax" (0.7 gram) were added to acetone (25 cc.) which was held for 5 minutes at 58° C. The concentrated acetone solution was then rapidly added to 1500 cc. of slowly stirred water, at room temperature. The waxed explosive was filtered off and examined under ultra-violet light.

The following table furnishes another indication of the relation between the visual examination and the Drop Test sensitivity of the ex-

violet light. This technique was found to be important since in some cases where a desired reduction in sensitivity was not secured by the addition of a definite amount of "wax" present which was piled up on some crystal faces while others were left uncoated. The method of application was found to be at fault and by changing this a better coating was obtained. Since excessive amounts of "wax" or inert material may lower the brisance of the explosive composition, the determination of the presence of non-uniform coating by the "wax" through the technique of examination by ultra-violet light, eliminated the necessity of adding even larger amounts of brisance lowering "wax."

In another instance in which a decrease in sensitivity did not accompany an increase in the percentage of "wax" added, examination of the coated material showed the presence of brilliantly fluorescing spherulites, scattered through the mass. Crushing of these spherulites showed the absence of any crystals within them as well as did treatment with a solvent in which only the "wax" was soluble. Incompatibility was found to be a large part of the trouble. The wax was found to have an electrical charge similar to that on the explosive; and the adhesive force of wax was much stronger than that of wax to explosive. In consequence, spherulites of wax were formed during the stirring of wax and explosive. Neither chemical analysis nor microscopic examination in ordinary light were as effective as the ultra-violet light examination in revealing the source of the trouble.

We claim:

1. In the art of phlegmatizing organic explosives, the method which comprises subjecting

particles of such an explosive to treatment for the purpose of applying to them a coating of a phlegmatizing wax which exhibits fluorescence, after the said treatment exposing the so treated particles of explosive to ultraviolet light, and while the said so treated particles of explosive are being exposed to said ultraviolet light, examining the said so treated particles of explosive to determine the distribution of said wax with respect to said particles of explosive from the fluorescence exhibited by the said wax which became associated with said particles of explosive as a result of the said treatment.

2. In the art of estimating the distribution of a phlegmatizing fluorescent wax with respect to particles of an organic explosive which have been subjected to a treatment for the purpose of coating them with said wax, the method which comprises exposing said so treated particles to ultraviolet light; and while said so treated particles are being exposed to said ultraviolet light, examining the said so treated particles to determine the distribution of said wax with respect to said particles from the fluorescence exhibited by the said wax that became associated with said particles as a result of the said treatment.

3. The method of estimating the phlegmatizing action of a fluorescent wax upon particles of an organic explosive or the effect upon its phlegmatizing action of the method used in applying the said wax to the particles of said explosive, the said method comprising subjecting the said particles of explosive to a treatment for the purpose of applying a fluorescent phlegmatizing wax to the surface of said particles, after such treatment exposing at least a portion of the treated particles to ultraviolet light, and while the said so treated particles are being exposed to said ultraviolet light, ex-

amining them to determine the extent of non-fluorescent area exhibited by them, whereby an estimate of the impact sensitivity of the said treated particles of explosive may be made.

5. The method of estimating the phlegmatizing action of a fluorescent wax upon particles of an organic explosive or the effect upon its phlegmatizing action of the method used in applying the wax to the particles of said explosive, the
10 said method comprising subjecting the said particles of explosive to a treatment for the purpose of applying a fluorescent phlegmatizing wax to the surface of said particles, after such treatment exposing at least a portion of the treated particles to ultraviolet light; and while the said so treated particles are being exposed to said ultraviolet light, photographing the said so treated particles through a filter which filters out ultraviolet light to obtain a record of the
15 distribution of the fluorescence of the said wax that became associated with said particles of explosive as a result of said treatment.
